UNITED STATES PATENT OFFICE.

GEORGE FRANKLYN MATTESON, OF ROCKY HILL, CONNECTICUT, ASSIGNOR, BY MESNE ASSIGNMENTS, TO THOMSON-NATIONAL PRESS COMPANY, INC., OF LONG ISLAND CITY, NEW YORK, A CORPORATION OF DELAWARE.

INK FOUNTAIN.

Application filed December 20, 1922. Serial No. 608,101.

To all whom it may concern:

Be it known that I, GEORGE FRANKLYN MATTESON, a citizen of the United States, residing at Rocky Hill, in the county of 5 Hartford and State of Connecticut, have invented certain new and useful Improvements in Ink Fountains, of which the following is a specification.

My said invention relates to an ink fountain for printing presses and it is an object of the invention to provide improved means for adjusting the feed.

Referring to the accompanying drawing which is made a part hereof and on which 15 similar reference characters indicate similar parts,

Figure 1 is an elevation of my device viewed from one side, and

Figure 2 is a rear elevation of the same.

20 In the drawings reference character 10 indicates the frame of the fountain which may consist of a casting of any convenient shape and which has an oblique partition 11 dividing its interior into upper and lower parts.

25 In the upper part there is an ink supply in contact with the ink cylinder 12 and resting on a blade 13. The ink cylinder has at its end a ratchet 14 driven by a pawl 15 on a rockarm 16. The rockarm is connected by

30 a link 17 to a rocking bent lever 20 carrying at its end a roller 21 which rests on a rotary cam 22. It will be seen that as the cam revolves the lever 18 will be rocked and so cause the pawl to drive the ratchet and the ink cylinder. In so rotating the cylinder 35 takes up ink from the supply at the rear thereof and carries it around for application to a ductor roller (not shown).

As one expedient for regulating the supply 40 of ink I have provided means to limit the return throw of the lever 18. As shown

this lever is provided with a spring 23 secured to the frame 10 at 24 for returning it against the action of the cam. An abutment 45 is provided to limit such return movement, said abutment consisting of a rod 25 mounted in the bore of a hollow bracket 26 which is here shown as formed integral with the frame 10. The bracket is cut away at

50 one side to form an opening through which a pin 27 projects, this pin extending into the bolt 25 but being free to swing on its own axis and carrying at its outer end a handle 28 which may be in the form of a round

button fixed to the pin. Between the handle 55 and the bolt 25 the pin is cut away throughout half its circumference leaving a half moon shaped part 29 adapted to engage with any one of a series of teeth 30 on the bracket. It will be seen that by turning the pin 60 to move the detent out of engagement with the teeth the bolt may be moved in the direction of its length to arrest the lever 18 at an earlier or later stage in its movement and thus cause the pawl to move the ratchet 65 through a segment varying from several teeth to none at all, there being of course no movement of the ink cylinder in the latter case.

The adjustment hitherto described affects 70 the arc through which the cylinder rotates at each stroke of the lever 18. I provide another adjusting means for determining the thickness of the film of ink on the cylinder. For this purpose the blade 13 is made 75 of resilient material and is bent upward at its free end so as to lie in a plane approximately radial with respect to the ink cylinder. This causes ink to be cut from the cylinder in an effective manner similar to 80 the cutting action exerted by a tool on a cylinder in a lathe. A series of pressure distributing plates 31 are located underneath the blade 13 and extend across the same. These pressure distributing plates are acted 85 upon by a series of screws 32 located in the frame 10 and here shown as passing through holes in the outer wall and another hole in the partition 11.

While I have shown and described a preferred form of my invention I do not limit myself strictly to what is here shown and disclosed but only as indicated in the appended claims.

Having thus fully described my said invention, what I claim as new and desire to secure by Letters Patent, is:

1. In an ink fountain, an ink cylinder, a ratchet connected thereto, a pawl for actuating the ratchet, means for moving the 100 pawl positively in one direction, resilient means for returning it, a slidably mounted bolt for limiting the action of said resilient means, a bracket in which the bolt is slid- 105 able, said bracket having a series of teeth arranged parallel to the line of movement of the bolt, and means movable with the bolt for engaging the respective teeth to vary

the action of the ratchet, substantially as set forth.

2. In an ink fountain, an ink cylinder, a ratchet connected thereto, a pawl for actuating the ratchet, means for moving the pawl positively in one direction, resilient means for returning it, a bolt for limiting the action of said resilient means, a bracket in which the bolt is movable, said bracket having a series of teeth, and an oscillating pin projecting laterally from the bolt the shank of said pin being crescent shaped in cross section for engagement with the respective teeth of said series, substantially as set forth.

15 3. In an ink fountain, an ink cylinder, means for rotating the same, means for adjusting the thickness of the film on the cylinder comprising an integral resilient blade mounted beneath the cylinder and bent at 20 its forward end approximately into a plane radial with respect to said cylinder, and means for adjustably positioning the free end of the blade, substantially as set forth.

4. In an ink fountain, the combination of 25 an ink cylinder, a ratchet connected to the cylinder, a pawl engaging the ratchet, a bent lever having upright and horizontal arms the upright arm being connected to said pawl, a cam engaging the horizontal arm to 30 move the lever in one direction, a spring connected to the upright arm to return the lever, and means acting on said upright arm for adjustably limiting the return stroke of the lever thereby limiting the rotation of 35 the ink cylinder, substantially as set forth.

5. In an ink fountain, an ink cylinder mounted at one side thereof, a ratchet on the cylinder, a pawl therefor, a lever connected to the pawl, means to reciprocate the lever, 40 a bearing formed on one end of the fountain, a bolt for limiting the return movement of the lever slidably mounted in said bearing, and means for securing the bolt in various positions of adjustment, substan- 45 tially as set forth.

6. In an ink fountain, an ink cylinder extending along an upper edge of the fountain, a pivot at a diagonally opposite edge, a lever on said pivot having an upright arm 50 and a horizontal arm adjacent a bottom edge of the tank, an operating cam engaging said horizontal arm to move the lever in one direction, pawl and ratchet mechanism for operating the cylinder, and a link connect-

ing said mechanism to the upright lever 55 arm, substantially as set forth.

7. In an ink fountain, an ink cylinder extending along an upper edge of the fountain, a pivot at a diagonally opposite edge, a lever on said pivot having an upright arm and a horizontal arm adjacent a bottom edge of the tank, an operating cam engaging said horizontal arm to move the lever in one direction, pawl and ratchet mechanism for 60 operating the cylinder, a link connecting 65 said mechanism to the upright lever arm, a spring below the link secured to the fountain at one end and to the upright lever arm at the other, a bolt slidably mounted on the fountain for limiting the return movement 70 of said upright lever arm, and means for securing said bolt in various positions of adjustment, substantially as set forth.

8. In an ink fountain, an ink cylinder extending along an upper edge of the fountain, a pivot at a diagonally opposite edge, a lever on said pivot having an upright arm and a horizontal arm adjacent a bottom edge 75 of the tank, an operating cam engaging said horizontal arm to move the lever in one direction, pawl and ratchet mechanism for 80 operating the cylinder, a link connecting 85 said mechanism to the upright lever arm, means acting in opposition to said cam to return the lever, and adjustable means for limiting the return movement of said upright arm, substantially as set forth.

9. In an ink fountain, an ink cylinder, means for rotating the cylinder including 90 an oscillating lever, means for moving the lever positively in one direction, resilient means for returning it, a bolt lying in the plane of movement of the lever, said bolt being mounted to slide toward and from the lever, and means for securing the bolt in various positions of adjustment to vary the 95 return stroke of the lever, substantially as set forth.

In witness whereof, I have hereunto set my hand and seal at Hartford, Connecticut, this 18th day of December, A. D. nineteen 100 hundred and twenty-two.

GEORGE FRANKLYN MATTESON.
